[57] CLAIM

The ornamental design for a modular shelf stand, as
shown and described.

DESCRIPTION

FIG. 1 is a perspective view of a modular shelf stand
showing my new design;

FIG. 2 is a top plan view thereof, with the surface shading
partially shown for ease of illustration;

FIG. 3 is a front elevational view thereof, the rear being
identical thereto;

FIG. 4 is a side elevational view thereof;

FIG. 5 is a bottom plan view thereof; and,

FIG. 6 is a view similar to FIG. 3 that incorporates the
shelves shown in FIGS. 1-5 and further illustrates a
second embodiment with four shelves, with an additional
fifth shelf shown in broken lines for illustrative
purposes only. This broken line showing of a shelf
forms no part of the claimed design.
